UNITED STATES PATENT OFFICE.

CASPAR KAPPINGER, JR., OF KUFSTEIN, AUSTRIA-HUNGARY.

DESIGN FOR A CURTAIN-SUSPENDER.

45,597.

Specification for Design.

Patented Apr. 14, 1914.

Application filed January 30, 1912. Serial No. 674,402. Term of patent 3½ years.

To all whom it may concern:

Be it known that I, CASPAR KAPPINGER, Jr., a subject of the Emperor of Austria-Hungary, residing at Kufstein, Tyrol, Austria-Hungary, have invented a new, original, and ornamental Design for Curtain-Suspender, which is shown in the accompanying drawing.

The figures show my new design, Figure 1 representing a front view, and Fig. 2, a side view of the curtain suspender.

b is a ring which is threaded on the cur-

tain rod; c, a bracket connected to the ring; d, f, a double-armed lever which is pivoted to the bracket c at e. d and c form a clip to receive the curtain. g is a spring acting on said clip.

I claim:—

The ornamental design for a curtain suspender as shown and described.
